UNITED STATES PATENT OFFICE.

NATHAN A. RACHLISS, OF NEW YORK, N. Y.

METHOD OF MAKING SIGNS.

1,074,461.

Specification of Letters Patent. Patented Sept. 30, 1913.

Application filed September 10, 1912. Serial No. 719,516.

To all whom it may concern:

Be it known that I, NATHAN A. RACHLISS, a citizen of the United States, and a resident of the city of New York, borough of the Bronx, in the county and State of New York, have invented a new and Improved Method of Making Signs, of which the following is a full, clear, and exact description.

My invention relates to an improved method of making sign letters, characters, and the ornaments incidental to signs.

It is an object of my invention to produce improved sign letters and the like on sign-boards, from plastic material, such as plaster of Paris, molten or fused metals, alloys, amalgams, fictile or other materials, that become hard and set from a condition of plasticity or fluidity, and hereinafter referred to as moldable material.

20 A further object of my invention is to provide an improved method and means whereby the letters may be cheaply produced, and have increased strength and wearing qualities.

25 In carrying out my invention use is made of a combined templet and mold in the form of a shell having the contour of the letter or character to be formed, so that the shell may be placed on a signboard of wood, metal, or other suitable material to trace the outline of the letter or character, the shell being adapted to receive a charge of moldable material for molding and pressing the letter in place over interlocking and reinforcing elements.

The invention will be more particularly explained in the specific description herein-after to be given.

Reference is to be had to the accompanying drawings forming a part of this specification, in which similar characters of reference indicate corresponding parts in all the views.

45 Figure 1 is a plan view illustrating a portion of a signboard having the outline of a letter produced thereon as the first step in my improved process; Fig. 2 is a similar view with a series of headed interlocking and reinforcing elements driven into the 50 sign following the general contour of the letter; Fig. 3 is an under side view of the shell forming the combined templet and mold, the same being indicated as charged with plastic material; Fig. 4 is a plan view 55 with the mold pressed into place over the

driven elements; and Fig. 5 is a cross sectional view.

In carrying out my invention a base is provided, consisting of any suitable sign-board material, preferably of wood, part of which is indicated by the numeral 10, and a shell 11, desirably formed of metal, and corresponding in profile with the letter to be formed is placed on said board and the outline of the letter traced on the board, as indicated by the numeral 12 in Fig. 1. Elements or formations to form an interlock between the molded letter and the board are provided. In the illustrated example, elements 13 are shown driven into the board, a series of said elements being employed following the general contour of the letter, character or figure, as shown in Fig. 2, said elements desirably being formed of headed nails or tacks, as shown. The shell 75 11, which is open at the under side is now filled with a charge of moldable material 14. A desirable material is composed of plaster of Paris, with glue or other sizing, and preferably mixed with asbestos fibers. 80 The edges of the shell at the back of the letter or other character are on the same plane at all points, so that the edges constitute strike edges over which a "strike" may be drawn to remove any surplus material and smooth the back of the letter. 85 The shell having been charged with the material and smoothed, it is then pressed onto the signboard at the outline 12, and over the reinforcing and interlocking elements 90 or equivalent formations. The shell or mold with the moldable material, is firmly pressed into place, the said material is permitted to harden and become set; the shell is then removed, leaving the material in the 95 form of a letter or character, and any suitable coloring material or gilding may be applied to the face of the letter, directly onto the moldable material. Coloring may be admixed with the material if desired. 100 Advantageously before placing the moldable material in the shell, the inner face of the letter is coated with oil, if plastic material is employed, to prevent the mold from adhering to the plastic material. In case 105 of molten metal, amalgams, or the like, being employed, the coating material will vary accordingly.

My invention results in the production of signs at a minimum cost and with great 110

facility, and the letters or other characters are adapted to receive ordinary paint, gilding and other surfacing in great variety.

Having thus described my invention, I claim as new, and desire to secure by Letters Patent:—

1. The herein-described method of forming signs, consisting in placing on a sign-board a hollow mold having a profile of the character to be formed, marking the outline of the character on the board where the character is to be traced, then providing the board within the outline with elements to interlock the board and the character to be produced, then charging the mold with moldable material then molding the character by pressing the mold charged with said moldable material directly onto the board at said outline, over the mentioned elements, and then removing the mold after the moldable material has hardened.
2. A method of forming signs consisting

in producing on a signboard the outlines of the character to be formed, driving interlocking and reinforcing elements into the board within said outline, in a series approximately following the general contour of the character, then pressing against the board and over said reinforcing elements a hollow mold corresponding with the character and charged with moldable material, and coated on the inner face to prevent adhesion of the mold to the moldable material, permitting the moldable material to harden, and then removing said mold and finally finishing the said character.

In testimony whereof I have signed my name to this specification in the presence of two subscribing witnesses.

NATHAN A. RACHLISS.
